KEY CLICK ELIMINATION CIRCUIT

Theodore P. Kinn, Baltimore, Md., assignor to Westinghouse Electric & Manufacturing Company, East Pittsburgh, Pa., a corporation of Pennsylvania

Application August 12, 1938, Serial No. 224,568

4 Claims. (Cl. 173—66)

This invention relates to systems of radio telegraphy wherein the transmission of electromagnetic energy is periodically interrupted in accordance with telegraph code signals, and more particularly to an arrangement for preventing undesirable noises accompanying such interruptions.

A primary object of this invention is to accomplish the keying of radio transmitters in such manner as to eliminate the production of thumps, termed "key clicks," which are usually observable in radio receivers located within the range of the transmitter.

The interfering key clicks are caused by a high order of side-band frequencies produced by the sudden starting and stopping of oscillations. In order to eliminate the cause, it is necessary to provide some means whereby the oscillations are controlled to start and stop gradually instead of abruptly.

Another object of this invention is to modify the shape of the transmitted wave front by means of reactive elements interposed in the keying circuit and arranged in such relationship of electrical values as to form a critically damped oscillatory circuit.

A further object of this invention is to control the rate of increase and decrease of transmitted high frequency currents upon closure and opening of the keying mechanism.

Other objects and advantages will be apparent from the following description of the invention, defined particularly in the appended claims, and taken in connection with the accompanying drawing, in which:

Figure 1 shows schematically the keyed stage of a radio telegraphy transmitter incorporating the novel control circuit in accordance with this invention;

Fig. 2 shows the current characteristic upon closure of the transmitter key;

Fig. 3 shows the current characteristic upon opening of the key; and

Fig. 4 shows the resultant current wave form when combining Figs. 2 and 3, representing the complete cycle of closure and opening of the keying mechanism.

Referring to Fig. 1, only the final amplifier stage of the radio-telegraphy transmitter is shown schematically. To simplify the illustration of the operation of the keying system, the latter is shown to be applied to the final amplifier stage, the preceding stages and the oscillator being indicated by a conventional block diagram.

It is to be understood, however, that it may as

well be applied to other stages, or in some cases, to the master oscillator stage when the keying thereof is contemplated. The output of the preceding stages is coupled to the final amplifier stage by means of the radio frequency transformer 1 having primary winding 2 and secondary winding 3. One terminal of the secondary winding connects with the grid 4 of the power amplifier tube 5. The other terminal of the secondary winding 3 is connected to the negative terminal of the bias potential source, represented here by the battery 6, through a resistor 7, the positive terminal of the battery being connected to the cathode 8 of the power amplifier tube 5. The radio frequency currents are provided with a low impedance return path to the cathode 8 through the bypass condenser 9. The output of the tube 5 includes the primary winding 10 of the coupling transformer 11, the two terminals of the secondary winding 12 thereof being connected to the antenna 13 and ground 14, respectively. The anode 15 of the tube 5 connects to one terminal of the primary winding 10, the other terminal thereof being connected by means of conductor 16 to the positive terminal of the power supply source, schematically represented here by the battery 17, the negative terminal of which is connected to ground.

To complete the cathode circuit of the tube 5 to ground, an inductive reactance 18 is connected between cathode 8 and the anode 15 of the control tube 20, the cathode 21 of tube 20 being connected by means of conductor 22 to one of the contactors 23 of the key 24, the corresponding contact 25 thereof being connected to the conductor 26. Across the terminals of the battery 17, that is, between ground and conductor 16, is connected a relatively large capacity 27. In power supply systems of the rectified alternating-current type, the capacity 27 is usually incorporated in the form of a filter condenser. The grid circuit of the control tube 20 includes the grid 28 connected to contact 29 of the key 24, the corresponding contactor 30 thereof being connected to contactor 23 which, as previously described, connects to the cathode 21 of the tube 20. Between cathode 21 and the grid 28, there is connected a resistor 31 in series with the bias potential source schematically shown as the battery 32.

The various contacts and contactors of the key 24 are so arranged that upon pressing the key contactor 23 and contact 25 close prior to the successive closing of contactor 30 and contact 29. Returning to the cathode-anode por-

tion of the amplifier tube 5, it is seen that the cathode terminal of the inductance 18 in the cathode return circuit connects also to a resistor 33 in series with a fixed capacity 34 which 5 terminates at the conductor 16, and the other terminal thereof is connected to a similar resistance-capacity network comprising resistor 33' and capacity 34'.

The problem of key click elimination in a 10 radio transmitter is primarily the problem of controlling the rate of increase and decrease of the antenna current when the telegraph key is closed and opened. To properly control the fluctuation of current in the antenna circuit 15 necessarily means control of the power to one or more of the vacuum tubes in the radio transmitter. In the circuit of Fig. 1, the power in the vacuum tube 5 is controlled by means of periodic opening and closing of the power supply 20 circuit to the tube. In other words, the tube 5 represents a load for the power supply source 17. In order to obtain the desired result, it is advantageous to utilize a control tube which is the primary means for disrupting the 25 flow of current in the anode-cathode circuit of the amplifier tube 5, and to control the actuation of the control tube 20 in a secondary circuit in which there is a very small amount of current flow in comparison with the one in the 30 primary circuit. The secondary circuit referred to is the grid circuit of the control tube 20, the key 24 effecting initiation of conductivity of the control tubes by means of short circuiting the bias potential of the source 32 whereby the grid 35 28 is directly connected to the cathode 21 upon closure of the key 24.

The various supply sources for the anode potential and grid potentials of the tubes may be batteries, as shown here for the purpose of simplifying the illustration, or rectifiers or generators may be employed. The condenser 27 is a necessary part for the proper functioning of the system, and when generators or batteries are used for the power source, it should be incorporated 45 as indicated here. However, when a rectifier-type power supply is used, the condenser 27 is usually an inherent part of such supplies and may be omitted.

In describing the operation of the system, the 50 circuit functions as follows: When the key 24 is closed, the contactor 23 and contact 25 close slightly before contactor 30 and contact 29 whereby the negative terminal of the battery 17 is connected to the cathode 21 of the control tube 20. 55 However, due to the slight time difference in the closure of the contactor 30 and contact 29, the grid 28 of the control tube 20 remains at a cutoff value of potential from the battery 32 and non-conductive until the latter contacts close, 60 short-circuiting the grid resistor 31 and the battery 32, whereby the blocking bias of the control tube is removed. The primary keying circuit to complete a path for the current from the supply 17 to the amplifier tube 5, therefore, is 65 actually made inside the tube 20; that is, by its spaced current path, and sparking which would normally occur when disrupting this circuit by a switch is entirely eliminated. Assuming now 70 conductivity of the tube 20, the operating potential for the anode 15 of the tube 5 will not reach maximum value immediately due to the action of the reactive components in the circuit, namely, the inductance 18, resistors 33 and 33' and condenser 34 and 34'. The gradual rise of 75 this voltage is due to the fact that the values

for the reactive components mentioned are so chosen as to form a critically damped oscillatory circuit.

After the anode voltage of the tube 5 has reached its normal value and the key 24 is opened, 5 power is removed by opening of the contacts 23 and 25. At this point, the advantages in the operation of the system are clearly observable as follows: After the anode voltage reached a steady value, condensers 34 and 34' are both 10 charged with the same potential; that is, the full anode potential, and, therefore, when contactor 23 and contact 25 are separated, it actually opens the cathode return to the negative terminal of the source 17. At the contact points 15 at this instant, however, there is no potential difference and, therefore, no sparking can occur. The reason for this is that contacts 30 and 29 actually open first, and if the tube 20 is of the mercury or gas-filled type, the bias potential will control only the starting of the tube and not its cutoff. The second action which occurs on opening the key 24 is that the energy stored in the circuit, comprising of the inductance 18, resistors 30 and 33' and condensers 34 25 and 34', is again controlled by the resonant condition of the circuit whereby the anode voltage decreases to zero gradually, as shown in Fig. 3. The net result for the closing and opening cycle of the key 24 is the combination of the two curves 30 of Figs. 2 and 3, as shown in Fig. 4, which is the ideal wave form for eliminating key clicks.

In a practical embodiment for keying a transmitter, the following values for the reactive components were found to give good results. 35

Inductance 18	henries	10
Condenser 34'	microfarad	.5
Condenser 34	do	.15
Resistor 33	ohms	1000
Resistor 33'	do	2000

The control tube 20 was of the mercury vapor grid-glow type used for industrial control identified as type KU-628.

In operation, the contacts 23 and 25 close first, applying approximately 3000-volt potential of the source 17 to the anode of the control tube 20, which, however, will not break down until contacts 30 and 29 are closed removing the blocking bias from the grid 28. The anode circuit for the amplifier tube is actually closed by the control tube 20, and no sparking at the contacts of the key 24 occur. At the break, when opening the key 24, contacts 30 and 29 open first, 55 which has no effect on the tube operation, for once the control tube is "ionized," the grid 28 loses control. Therefore, when the key is released and contacts 23 and 25 open, they perform the duty of breaking the circuit. However, no sparking results again, due to the action of the condenser 34' in conjunction with the filter capacitor 21, both being fully charged capacities on either side of the contacts 23 and 25. The control tube need not be of the gas-filled type, and an ordinary vacuum tube may be employed 60 in its place, in which case, contacts 23 and 25 may be eliminated by a permanent connection between them, and the control of both make and break accomplished by the grid control of the contacts 30 and 29. 70

What is claimed is:

1. In a keying system for radio telegraph transmitters, a vacuum tube having anode, cathode and at least a control electrode, a power supply for energizing said tube, one terminal 75

- of said supply being effectively connected to said anode and another terminal thereof to said cathode, whereby said tube forms a load for said supply, a keying circuit interposed between said supply and said tube including means for interrupting the connection to said cathode at a relatively fast rate, and means for controlling the rate of increase of current in said circuit during closure of said first mentioned means and the rate of decrease of said current upon opening thereof, comprising reactive elements in series and parallel relationship with respect to said load interposed in said circuit, said elements being so proportioned as to form a critically damped oscillatory circuit.
2. In a keying system for radio telegraph transmitters, a vacuum tube having anode, cathode and at least a control electrode, a power supply for energizing said tube, one terminal thereof being effectively connected to said anode and another terminal to said cathode whereby said tube forms a load for said supply, a keying circuit interposed between said supply and said tube including means for interrupting the connection to one of said electrodes at a relatively fast rate, and means for controlling the rate of rise of current in said tube during closure of said first mentioned means and the rate of decay of said current upon opening thereof, comprising reactive elements in series and parallel relationship with said load interposed in said circuit, said elements being so proportioned as to form a critically damped oscillatory circuit.
3. In a keying system for radio telegraph transmitters, a vacuum tube for amplifying high frequency currents having cathode, anode, and at least one control electrode, a power supply for energizing said tube, one terminal of said supply being effectively connected to said anode and another terminal thereof to said cathode, a fixed capacity between said terminals, a keying circuit for interrupting the flow of current from
- said supply to said tube at a relatively fast rate, including a current interrupter, and means for controlling the rate of increase of anode current of said tube during closure of said interrupter and the rate of decrease of said anode current upon opening of said interrupter, comprising an inductance serially interposed between cathode and said other terminal of said supply, a fixed capacity and a resistance in series connected effectively in parallel between cathode and the anode terminal of said supply and another fixed capacity and resistance in series connected effectively in parallel with said supply, said series and parallel elements being so proportioned as to form an oscillatory circuit critically damped in character.
4. In a keying system for radio telegraph transmitters, a keying circuit and a keyed circuit interconnected by means of electrical coupling elements, a source of current so related to said keyed circuit as to be periodically interrupted by said keying circuit, said last-mentioned circuit including a control tube having anode, cathode and control electrode, the anode-cathode path of said tube forming a conductive connection between said source and said keyed circuit, a current interrupter including a plurality of contactors in said keying circuit, one pair of said contactors operating to connect said source to said cathode and another pair to connect said grid to a supply of bias potential, whereby upon closure of said contactors said tube is energized to conductively pass current from said source to said keyed circuit, said coupling elements comprising an inductance and capacities and resistive elements so related as to form a critically damped oscillatory circuit, whereby the current in said keyed circuit is caused to rise gradually upon closure of said contactors and to decrease gradually upon opening thereof.

THEODORE P. KINN.
